UNITED STATES PATENT OFFICE.

HARRISON J. MITCHELL, OF BELOIT, WISCONSIN, ASSIGNOR TO THE BERLIN MACHINE WORKS, OF BELOIT, WISCONSIN, A CORPORATION OF WISCONSIN.

FASTENING MEANS FOR PLANER-HEADS.

1,049,589.

Specification of Letters Patent.

Patented Jan. 7, 1913.

Application filed December 14, 1908. Serial No. 467,417.

To all whom it may concern:

Be it known that I, HARRISON J. MITCHELL, a citizen of the United States, residing at Beloit, in the county of Rock and State of Wisconsin, have invented certain new and useful Improvements in Fastening Means for Planer-Heads and the Like, of which the following is a specification.

This invention pertains to improvements in the heads or cylinders of planers, and relates more particularly to improved and novel means for fixedly holding and securing beading knives or the like in place. Each of such knives has a base, preferably of dovetail or similar conformation, adapted to fit in a correspondingly-shaped or undercut groove or slot on the planer cylinder surface, the bases of the beading knives being held in firm engagement with the walls of such grooves by suitable means which will force them into such position or relation.

In my preferred embodiment of the invention the bases of the knives are made so as to be capable of expansion, and I employ expanding means such as tapered screws to enlarge the bases and cause them to press firmly against the undercut sides of the groove.

In the accompanying drawing, which forms a part of this specification, I have illustrated a preferred embodiment of the invention, and in these drawings—Figure 1 is a fragmentary perspective view of a planer cylinder equipped with the invention, the cylinder also having an improved stop for properly positioning the beading knives; Fig. 2 is a cross-section on line 2—2 of Fig. 1; and Fig. 3 is a rear face view of the beading knife shown in Fig. 2.

By referring to the drawings it will be made apparent that the planer head or cylinder 11, only a portion of which is shown in any of the figures, has extended across its cylindrical face or periphery one or more dovetail or undercut grooves 12 adapted to receive and accommodate the bases of the beading knives. The bottom of this groove I have provided with the reference character 13, while to the rear side wall and the front side wall I have applied the reference characters 14 and 15, respectively.

A preferred embodiment of the invention is shown in Figs. 1, 2 and 3, in which the beading knife 16 has a base 17 shaped to fit

within the groove 12 beneath the overhanging walls 14 and 15, which base is of substantially no greater width than the knife itself and is vertically divided or slotted at 18, as shown, and also equipped with a tapered screw hole intersected by this slot or cut, this hole being intended to accommodate a tapered tightening screw 19. As is obvious, the turning of this screw so as to force it inwardly will enlarge the base, spreading its two portions apart so that they will firmly and securely press against the walls of the groove, thereby holding the knife in fixed operative position. The tapered screw hole is made somewhat inclined to the plane of the bottom of the groove so as to facilitate the turning of the screw by a screw-driver of the ordinary character and to avoid the necessity of a laterally extending base. In the embodiment illustrated one portion of the base is pressed rearwardly into the back part of the groove, while the other portion is forced forwardly beneath the front wall of the groove, so that in each instance the knife is securely held from moving out of its correct operative position. Such beading knives are frequently used on a planer cylinder also equipped with straight-edge planing knives, and in order that the latter may be properly jointed during the rotation of the cylinder or head, it is necessary to take out the beading knives, and of course they should be replaced in exactly the same positions which they previously occupied. To facilitate this replacement the undercut or dovetail grooves may be supplied with one or more stop or abutment blocks also shaped to conform substantially to the cross-section of the groove. One form of such block is shown in Fig. 1 at 21. As is clearly illustrated, this block is provided with a substantially central threaded hole therethrough which receives a tightening screw 22 bearing against the bottom face of the groove and forcing the block upwardly so that its inclined sides are brought into firm engagement with the inclined side walls of the undercut groove, the friction between the parts being sufficient to prevent dislodgment. After one or more of these stop or abutment blocks have been properly positioned and tightened in the grooves, the knives coöperating therewith may be readily

taken out and replaced without difficulty in exactly the same positions which they previously occupied.

To those skilled in the art it will be readily understood that the beading knives and stops are to be grouped in the holding grooves in conformity to the form and style of beading to be produced on the boards or lumber, and in the drawing of this application I have not attempted to show any such arrangement of knives, but have merely indicated in Fig. 1 a plurality of such knives.

The various features of detail herein shown and described may be changed and modified within wide limits without departure from the substance and essence of my invention, and without the sacrifice of any of its benefits and advantages.

I claim—

1. The combination of a planer cylinder having an undercut groove on its outer surface, a knife having a dovetail base adapted to fit in said groove, said base having a threaded hole disposed transversely of the cutting edge of said knife, and inclined to the bottom of said groove, said base having also a slot dividing the base and intersecting said threaded hole in the plane of its axis, and

a tapered screw threaded into said hole to spread the slotted base of the knife and force the beveled edges thereof against the walls of said groove to securely hold the knife in operative position, substantially as described.

2. The combination of a planer cylinder having a longitudinally extending undercut groove on its periphery, a planer knife having a dovetail base of substantially the same width as the body of the knife and adapted to fit in said groove, said base having a tapering screw-threaded hole extending therethrough longitudinally of the undercut groove and inclined to the bottom of said groove and having also a slot intersecting said hole and dividing the base, and a tapered screw threaded into said hole to force the sides of the base apart, whereby the beveled edges thereof are forced into engagement with the undercut walls of the groove to securely hold the knife in operative position, substantially as described.

HARRISON J. MITCHELL.
